UNITED STATES PATENT OFFICE.

HENRY GUY CARLETON, OF NEW YORK, N. Y., ASSIGNOR TO THE CARLETON ELECTRIC COMPANY, OF SAME PLACE.

ELECTRIC LOCK.

SPECIFICATION forming part of Letters Patent No. 657,853, dated September 11, 1900.

Application filed January 13, 1900. Serial No. 1,298. (No model.)

To all whom it may concern:

Be it known that I, HENRY GUY CARLETON, a citizen of the United States, residing at New York, county of New York, and State of New York, have invented certain new and useful Improvements in Electric Locks, fully described and represented in the following specification and the accompanying drawings, forming a part of the same.

10 This invention relates to certain improvements in electric locks.

One of the objects of the invention is to provide a simple, cheap, and efficient lock in which the withdrawing mechanism for the 15 movable-engaging part, such as the bolt or keeper, shall be normally inoperative to move said part, but in which a controller is provided which may be caused to engage the movable engaging part, thereby rendering 20 the withdrawing mechanism operative.

Another object of the invention is to produce an electric lock in which the withdrawing mechanism for the movable engaging part, such as the bolt or keeper, is normally 25 inoperative to move said part and in which a controller is provided to render the withdrawing mechanism operative, the controller being actuated by electrical means, the circuit for which is preferably, though not necessarily, controlled by devices actuated from 30 the withdrawing mechanism.

With these and other objects in view the invention consists in certain construction and in certain parts, improvements, and combinations, as will be hereinafter described, and more fully pointed out in the claims hereunto appended.

In the accompanying drawings, which form 40 part of this specification, and in which like characters of reference indicate the same parts, Figure 1 is a view in side elevation of the lock and casing, one of the sides of the casing being removed to show the operative parts of the lock. Fig. 2 is a vertical sectional view taken on the line 2 2 of Fig. 1. Fig. 3 is a horizontal sectional view taken on the line 3 3 of Fig. 1 looking in the direction of the arrow in said figure.

Referring to the drawings, which show one

concrete embodiment of the invention, 1 indicates a lock-casing in which the operative parts of the lock are contained. In the lock the movable engaging part consists of a sliding bolt 2, the said bolt being designed to engage a stationary keeper which is not shown. 50 It is obvious, however, that the keeper might be made the movable part, if desired. The movable bolt 2 passes, as is usual, through an opening in the front side of the casing and is provided with a stem 3, which works through 55 an opening in a supporting-bracket 4. The bolt is provided with a rim or projection 5 and is held forward to its duty by a spring 6, which surrounds the stem. In the lock shown two sets of withdrawing mechanism are provided, though one set may be dispensed with in some cases. These sets of withdrawing mechanisms may be widely varied in form and construction. Preferably, however, the operative devices for them will lie on opposite sides of the lock. In the lock shown one of the withdrawing mechanisms includes a slide 7, said slide being supported by the bracket 4, before described, and also by another similar bracket 8. The slide 7 is provided with any suitable means for withdrawing the bolt, and the withdrawing mechanism with suitable actuating devices. In the construction shown the slide carries a pin 9, which engages the rim or projection 5, before 60 referred to, and while the actuating device for the slide may be widely varied in construction in the lock shown it includes a rotating cam 10, which engages a projection 11, carried by the slide, said cam being secured 65 to a squared knob-shaft 12, which is operated by a knob 12'.

It will be noticed that all the parts of the withdrawing mechanism just described are normally in engagement, so that when the 70 knob is operated the bolt will be withdrawn.

In addition to the withdrawing mechanism before described there is provided a second withdrawing mechanism, which is independent of the one hereinbefore referred to. 75 While this second withdrawing mechanism may be widely varied in form and construction, in the lock shown it includes a slide 13,

which is suitably supported in the brackets 4 and 8. This slide 13, in the construction shown, is not provided with means for engaging the bolt or other movable engaging part, but its movement is made effective to operate said part by means of a controller. This controller may be also varied in construction, location, and arrangement. In the construction shown it consists of a part 14, 10 preferably constructed in the form of a hook, and it will preferably be arranged to move the slide 13, before described. While this may be accomplished in various ways, the controller will preferably be pivoted to the 15 slide, the pivotal point thereof being indicated at 15.

While the controller may be operated in any suitable manner, it will preferably be electrically operated. Various electrical devices 20 may be used to operate the controller; but in the construction shown there is provided a magnet, said magnet being supported by a bracket 16, located in the lock-casing. While any suitable form of magnet may be 25 used to effect the movement of the controller and while the magnet may operate directly upon the controller or through intermediate devices, in the construction shown the magnet is of the class known as a "club-foot" 30 magnet—that is to say, it is provided with a single coil 17, which surrounds one of the poles 18 of the magnet, said pole being of the ordinary description and the other pole consisting of a bent bracket-like part 19, which 35 is secured to the pole 18. In the construction shown the controller is arranged so as to form the armature for the said magnet, though this arrangement is not a necessary one. When, therefore, the magnet is energized, the 40 controller is turned on its pivot, and its hooked end is caused to engage the rim or projection 5, before referred to. The magnet may be located at any suitable point in the path of the controller. Preferably, however, it will 45 be arranged close to the pivotal point of the controller when the parts of the lock are in their normal position—that is, when the parts are in the position shown in Fig. 1. By thus arranging the magnet close to the pivotal 50 point of its controller-armature the poles of the magnet can be brought very close to the controller-armature. The attractive force of the magnet is thus exercised to the greatest possible advantage, and at the same time a 55 slight movement of arc near the pivotal point of the armature produces a very considerable movement at the operating end of the controller.

By referring to Fig. 1 it will be seen that 60 when the magnet is energized poles 18 19 of the magnet will draw the armature against them, and although the movement at the points where the poles operate in the first instance is a very slight movement, yet the 65 movement of the hooked or engaging end of the controller is of considerable extent. Fur-

thermore, as slide 13 is moved through its operating devices, to be hereinafter described, the controller will be held against the poles of the magnet, so that engagement of the 70 hooked end of the controller with the projection of the sliding bolt will be insured.

Any suitable actuating device may be provided for the slide 13. Preferably, however, the said actuating device will include a rotating cam 20, said cam being mounted on a squared knob-shaft 21, the knob 21' of which lies on the opposite side of the casing from knob 12', before described. The rotating cam 20 is arranged to engage a projection 22, 80 secured to the slide 13. The actuating device described operates to move the slide in one direction only, and in order to move it in the other direction there is provided a spring 23, which is secured to a pin 24, carried by a 85 slide, the other end of the spring being secured to the lock-casing 15 by a screw or in any other suitable manner.

Any suitable circuit or circuits may be provided for energizing the magnet before described. Preferably, however, the circuit will be open at two points, and preferably, also, it will be closed at one point by the movement of the withdrawing mechanism. In the construction shown a battery 26, located at any suitable point, is provided, said battery being connected with the magnet by a wire 27. Extending from the other side of the battery is a wire 28, which leads to a circuit-closer, shown as an ordinary push-button 29, which may be located at any suitable point. From the push-button is led a wire 30. While a circuit open at one point might be used and the wire led directly from the circuit-closer to the magnet, in the construction shown, as has been stated, the circuit is open at two points and is closed at one of the points by the movement of the withdrawing mechanism. Various devices variously located may be employed to effect the closing 105 of this circuit by the movement of the withdrawing mechanism; but these devices will preferably be located within the lock. In the construction shown, which represents a simple and effective form of circuit-closing device, the wire 30 leads to the rotating cam 20, said cam being provided with a recess 31. A suitably-mounted terminal—such, for instance, as a spring 32—is located within the casing, the end of said spring lying in the recess 31 and out of contact with the cam 20. From the spring 32 a wire 33 is led around the magnet. With the circuits described it will be seen that when the push-button 29 is operated and the knob 21' is turned the cam 125 20 will strike against the spring 32, closing the circuit through the magnet, causing it to attract the controller-armature. The movement of the controller-armature causes its hooked end to engage with the projection 5, 130 before described, and the bolt will be withdrawn. If, however, the knob 21' is operated

110
115
120
125
130

without operating the circuit-closer 29, the slide 13 will be operated, but there will be no movement of the controller-armature about its pivot, and the bolt therefore will not be withdrawn.

5 By providing a circuit open at two points a conservation of battery energy is effected, since the battery is not thrown into operation until the instant the lock is to be operated. This point is of importance in connection with the open-circuit batteries which are ordinarily used in devices of this class, as such batteries run down very quickly. It is not to be understood, however, that the 10 main features of the invention are limited to the use of open-circuit batteries, as batteries employing a closed circuit might be used therewith with slight modifications of construction.

20 The ordinary torsional springs will be used in connection with the knob-shafts, one of said springs being shown at 34 and operating upon knob-shaft 21. Suitable stops 35 36 are also provided to limit the movement of the 25 cams 20 and 10.

The constructions by which the various features of the invention may be carried into effect may be varied within wide limits. The invention therefore is not to be limited to the 30 specific constructions herein described.

What is claimed is—

1. In a lock, the combination with a movable engaging part, of a withdrawing mechanism, a controller which moves with the 35 withdrawing mechanism when the lock is to be opened, and electrically-controlled means for giving the controller a movement independent of the movement which it has under the influence of the withdrawing mechanism 40 to cause it to engage the movable part, substantially as described.

2. In a lock, the combination with a movable engaging part, of a withdrawing slide, a controller which moves with the slide when 45 the lock is opened, and electrically-controlled means for giving the controller a movement independent of the movement which it has under the influence of the withdrawing slide to cause it to engage the movable part, substantially as described.

3. In a lock, the combination with a sliding spring-held bolt, of a hand-operated withdrawing mechanism therefor, a controller which moves with the withdrawing mechanism 55 when the lock is to be opened, and electrically-controlled means for giving the controller a movement independent of the movement which it has under the influence of the withdrawing mechanism to cause it to engage the movable part, substantially as described.

4. In a lock, the combination with a movable engaging part, of a controller connected to one of said parts and moving therewith, a magnet for giving the controller a movement 60 independent of the movement which it has in common with the part to which it is connected

for causing it to engage the other part, and means for moving the slide, substantially as described.

5. In a lock, the combination with a movable engaging part, of a slide, a controller carried by one of said parts, a magnet for moving the controller to cause it to engage the other part, said controller forming the armature for the magnet and moving across the field thereof when the lock is opened, and means for moving the slide, substantially as described.

6. In a lock, the combination with a movable engaging part, of a slide and means for moving it, a controller moving with the slide and electrically-controlled means for giving the controller a movement which is independent of the movement it has with the slide for causing it to engage said movable part, where- 85 by the movement of the slide is made effective to open the lock, substantially as described.

7. In a lock, the combination with a movable engaging part, of a slide, a controller pivoted to the slide, a magnet, the attractive 90 force of which is exercised upon the controller to cause it to engage said movable part, and means for moving the slide, substantially as described.

8. In a lock, the combination with a movable engaging part, of a slide, a controller pivoted to one of said parts, a magnet for moving the controller to cause it to engage the other part, said controller forming the armature of the magnet and moving across the field thereof when the lock is opened, and means for moving the slide, substantially as described.

9. In a lock, the combination with a movable engaging part, of a withdrawing mechanism therefor, a controller carried by one of said parts, and a magnet by which the controller is actuated to engage the other part, said controller moving across the field of the magnet when the lock is opened, substantially as described.

10. In a lock, the combination with a movable engaging part, of an actuating device, movable connections between said actuating device and the part, a controller moving with the connections, and a magnet lying in the path of movement of the controller and operating to give it a movement which is independent of the movement which it has with the connections to cause it to engage the movable part, substantially as described.

11. In a lock, the combination with a movable engaging part, of a slide, an actuating device therefor, a controller pivoted on the slide, and a magnet for which the controller 125 forms the armature and across the field of which it moves when the lock is opened, said magnet operating to cause the controller to engage the movable engaging part, substantially as described.

12. In a lock, the combination with a movable engaging part, of a slide, an actuating

device therefor, a controller pivoted on the slide, and a magnet lying in the path of movement of the controller and operating to cause it to engage said movable part, substantially 5 as described.

13. In a lock, the combination with a movable engaging part, of an actuating device, moving connections between the actuating device and movable part, a controller pivoted 10 to the connections, and a magnet located near the pivotal point of the controller and the poles of which are arranged close to the controller, said magnet operating when energized to cause the controller to engage the 15 said movable part, substantially as described.

14. In a lock, the combination with a movable engaging part, of movable connections therefor, a controller pivoted to one of said parts, and a magnet located near the pivotal 20 point of the controller and having its poles arranged close to the controller, whereby the controller is caused to engage the other part, the controller moving across the field of the magnet when the lock is opened, substantially 25 as described.

15. In a lock, the combination with a movable engaging part, of a slide, an actuating device therefor, a controller pivoted to the slide, a magnet located near the pivotal point 30 of the controller and having its poles arranged close to the controller, said magnet operating when energized to cause the controller to engage said part, substantially as described.

16. In a lock, the combination with the movable engaging part of a withdrawing mechanism therefor including a rotating cam, electrically-controlled means whereby the withdrawing mechanism is made effective to move the engaging part, a suitable circuit for said 35 means, and means located within the lock-casing whereby the rotating cam operates to close the said circuit, substantially as described.

17. In a lock, the combination with a movable engaging part, of a withdrawing mechanism including an actuating device, and moving connections between it and the said engaging part, a controller, a magnet operating to cause said controller to engage said 45 part, a circuit for the magnet which is open at two points, and circuit-closing devices operated by the movement of the withdrawing mechanism to close the circuit at one of the points, substantially as described.

55 18. In a lock, the combination with a movable engaging part, of a slide, a controller moving with the slide, a magnet for causing the controller to engage said part, a circuit for the magnet normally open at two points 60 and means operated by the actuating device for closing the circuit at one of the points, substantially as described.

65 19. In a lock, the combination with a movable engaging part, of a slide, a controller moving with the slide, a magnet for causing the controller to engage said part, a circuit for the magnet normally open at two points

and means located in the lock-casing and operated by the actuating devices for closing the circuit at one of the points, substantially 70 as described.

20. In a lock, the combination with a sliding bolt, of two slides, means on one of the slides for engaging said bolt, a controller moving with the other slide, a magnet for causing 75 the controller to engage the bolt and actuating devices for the two slides lying on opposite sides of the lock, substantially as described.

21. In a lock, the combination with a sliding bolt, of two slides, actuating devices for each of the slides, said devices including rotating cams and operating knobs therefor, said knobs lying on opposite sides of the lock, means whereby one of the slides engages the 80 bolt, a controller pivoted on the other slide, a magnet for causing the controller to engage the bolt, a circuit for said magnet including the rotating cam for the slide which carries 85 the controller, said circuit being open at two points, a terminal for said circuit contained in the lock-casing, said rotating cam being arranged to strike the terminal and close the circuit when the lock is operated, substantially 90 as described. 95

22. In a lock, the combination with the movable engaging part including a recessed rotating cam, electrically-controlled means whereby the withdrawing mechanism is made effective to move the engaging part, a suitable circuit for said means said circuit including the recessed cam and a terminal lying in the recess, whereby the rotation of the cam closes the circuit, substantially as described. 100 105

23. In a lock, the combination with a movable engaging part, of a slide, a controller moving with the slide, a rotating cam for moving the slide, a magnet lying in the path of movement of the controller and operated when energized to cause it to engage said part, a circuit for said magnet which includes the 110 rotating cam, a terminal for the circuit lying in the casing and normally out of contact with the cam, but in a position to be struck by the cam when the same is rotated, and means for closing the circuit at another point, substantially as described. 115

24. In a lock, the combination with a bolt, of a slide, a controller pivoted to the slide, a club-foot magnet located near the pivotal point of the controller, the poles of said magnet being arranged close to the controller, the magnet being operative when energized to cause the controller to engage the bolt, substantially as described. 120 125

In testimony whereof I have hereunto set my hand in the presence of two subscribing witnesses.

HENRY GUY CARLETON.
